UNITED STATES PATENT OFFICE.

OSCAR S. JOHNSON, OF MAKOTI, NORTH DAKOTA.

KNOTTER-HEAD FOR BINDERS.

1,316,578.

Specification of Letters Patent. Patented Sept. 23, 1919.

Application filed June 12, 1917. Serial No. 174,295.

To all whom it may concern:

Be it known that I, OSCAR S. JOHNSON, a citizen of the United States, residing at Makoti, in the county of Ward and State 5 of North Dakota, have invented certain new and useful Improvements in Knotter-Heads for Binders, of which the following is a specification.

This invention relates to agricultural implements, and more particularly to knotter heads for binders.

The main object of the invention is to provide simple and efficient means whereby wear and lost motion in the tying mechanism of the knotter head of a binder may 15 be compensated for and the tying thereof accurately effected at the proper time.

After the tying mechanism for binders has been used to some extent, it sometimes 20 misses and oftentimes forms a knot in one end while the other end of the securing device slips through. This is owing to the fact that the knotter jaw wears a groove in the knotter jaw cam thereby causing lost motion 25 and preventing the knotter jaw from locking at the proper place, such as is necessary to cause the accurate tying of a bundle. It is to overcome this objection and insure 30 the accurate operation of the tying mechanism that this device is designed.

With the foregoing and other objects in view, which will appear as the description proceeds, the invention resides in the combination and arrangement of parts and in the 35 details of construction hereinafter described and claimed, it being understood that changes in the precise embodiment of the invention herein disclosed may be made within the scope of what is claimed without 40 departing from the spirit of the invention.

In the accompanying drawings:—

Figure 1 represents a side elevation with parts broken out of a knotter head-casting and breastplate equipped with this invention,

Fig. 2 shows a detail perspective view of the spring employed for holding the knotter jaw cam in operative engagement with the knotter jaw,

Fig. 3 is a plan view of the knotter jaw cam detached; and

Fig. 4 is a detail plan view.

In the embodiment illustrated, a knotter head casting 1 is shown having a breast-plate 2 of ordinary construction secured thereto and a knotter jaw cam 3 also car-

ried thereby, said cam being constructed in the form shown in Fig. 1 and secured to the casting 1 by a fastening element here shown in the form of a screw 4. This jaw 60 cam 3 tapers toward one end and has outstanding cam flanges 5, an aperture 6 being provided at its rear end for the passage of the securing screw 4.

A knotter of ordinary construction not 65 shown provided with the usual jaw operates in connection with the cam 3 to effect the tying operation.

The continuous operation of the device causes the knotter jaw to wear a groove in 70 the cam 3, and to overcome the objectionable lost motion occasioned thereby, I have provided a plate spring 7 which is secured at one end to the breast-plate 2, preferably by a bolt 8, one end of said spring being here 75 shown bent at right angles as indicated at 11 in Figs. 1 and 2, and which is passed through an opening 2' in the breast-plate to hold the spring against turning. This spring 7 is preferably made in the form of 80 a compound curve, and the free end thereof bears normally against the lower edge of cam 3 and operates to force it upwardly thereby presenting a new wearing surface for contact with the knotter jaw. Means 85 for adjusting the tension of this spring is here shown in the form of a set screw 9 which passes through the breast-plate 2 and engages the lower face of spring 7 and is 90 held in position by a lock nut 10 as is shown clearly in Fig. 1. Thus it will be observed that the cam 3 may have its position varied according to the tension of spring 7 and that this tension is regulated by said set screw although obviously other 95 means may be employed if found desirable.

The breast-plate 2 is here shown secured to the knotter head casting 1 by means of a bolt 11 held in operative engagement therewith by lock nuts 12.

It is well known in devices of this character that the knotter must revolve once around with the twine in order to tie a knot, and in so doing, it is necessary that the knotter jaw cam 3 be properly adjusted to 105 effect the tying operation, and this turning of the knotter in time will wear the groove above referred to, causing lost motion, which results in the knotter jaw locking at the wrong place.

The spring 7 which is herein employed for overcoming lost motion between the

100

110

parts, is made of steel and of a suitable thickness to prevent breakage and by disposing it as herein shown and described it is entirely out of the way of the other parts 5 of the knotter head. In order to attach this cam adjusting means it is only necessary to drill two holes in the breast-plate 2, one for the bolt 8 which connects spring 7 to said breast-plate and one for the set screw 9 which accomplishes the adjustment of the 10 tension of said spring and the oblong opening 2' for the passage of the hooked end or arm 11 of the spring.

From the foregoing description, taken in 15 connection with the accompanying drawings, the advantages of the construction and of the method of operation will be readily apparent to those skilled in the art to which the invention appertains, and while I have 20 described the principle of operation of the invention together with the device which I now consider to be the best embodiment thereof, I desire to have it understood that the device shown is merely illustrative and

that such changes may be made as are within 25 the scope of the claimed invention.

I claim:

The combination of a knotter jaw cam having a lateral projection on its lower edge and a breast-plate having an opening there- 30 in; of a flat spring metal strip bent in the form of a compound curve having a right angularly disposed arm at one end passed through the opening in the breast-plate to hold the spring against lateral movement, 35 a bolt securing said end to said breast-plate, the other end of said plate bearing flatly against said lateral projection on said cam, and a bolt adjustably mounted in said breast-plate and engaging the lower face 40 of said spring to force the free end thereof into yielding engagement with said cam.

In testimony whereof I affix my signature in presence of two witnesses.

OSCAR S. JOHNSON.
